UNITED STATES PATENT OFFICE.

MAZIE C. EDWARDS, OF NORWICH, CONNECTICUT.

SPOOL HOLDER.

Application filed May 27, 1920. Serial No. 384,656.

To all whom it may concern:

Be it known that I, MAZIE C. EDWARDS, a citizen of the United States of America, residing at Norwich, in the county of New London and State of Connecticut, have invented new and useful Improvements in Spool Holders, of which the following is a specification.

The object of the invention is to provide a simple and comparatively inexpensive device suitable for holding a spool of thread or cotton, or a ball of yarn under conditions which will be convenient to the seamstress or the operator in knitting or crocheting, and furthermore in such a way as to protect the same from dust and guard against snarling or tangling while presenting the loose end for access at all times, it being preferable to provide a holder with means whereby it may be attached to or suspended from a garment of the operator such as the waist or the skirt band, and with these objects in view the invention consists in a construction and combination of parts of which a preferred embodiment is shown in the accompanying drawings wherein:

Figure 1 is a side view of the device.

Figure 2 is a sectional view of the same taken in the plane of the axis of the receptacle.

Figure 3 is a transverse section on the plane indicated by the line 3—3 of Figure 2.

The holder consists essentially of a receptacle 10 which may, as shown be cylindrical in general form with a removable cap or covering 11 attached to the body of the receptacle by a threaded joint indicated at 12 and extending axially from the receptacle are knobs or trunnions 13 with which may be connected the extremities of a flexible suspending means such as a chain 14 provided at an intermediate point with an attaching device such as a safety pin 15 connected with the chain by a ring 16.

In the side wall of the body portion of the receptacle is arranged a guide or outlet opening 17 through which the end of the thread, cotton, or yarn may be directed so

as to be accessible to the operator for the removal of the desired length of material for use at any one time, and whereas, when the ball of yarn is serving or furnishing the material it may be arranged loosely in the receptacle, it is preferable, when thread or cotton is being used from a spool, to provide a spindle 18 as indicated in Figure 2 for arrangement in or about the axis of the receptacle, one end of said spindle being threaded as shown at 19 for detachable engagement with a socket 20, one of which may be arranged in each of the heads of the receptacles in alinement with the knobs or trunnions 13.

Obviously the holder may be suspended from the dress of the operator, or user to suit her preference so that the projecting end of the thread or yarn may be readily grasped as needed and withdrawn to the desired extent either for threading a needle or to provide the necessary slack in knitting or crocheting, and the revolvability of the receptacle with reference to the hanger or flexible supporting means provides for the movement of the guide outlet 17 to suit the direction in which the thread or yarn is being strained in feeding it from the receptacle.

The invention having been described as being what is new and useful is:

A holder for the purpose described having a cylindrical receptacle provided with a removable cap of complementary construction to the receptacle and removably secured thereto, the lid and the receptacle being provided with axial knobs constituting trunnions, a flexible suspending means engaging with said trunnions to rotatably support the receptacle when the lid is attached, and an axial spindle in the receptacle and engageable with sockets formed in the trunnion of either the receptacle or lid, the receptacle having a peripheral outlet perforation for the passage of a strand of thread.

In testimony whereof she affixes her signature.

MAZIE C. EDWARDS.
